UNITED STATES PATENT OFFICE.

CARL H. ROTH, OF NEWARK, NEW JERSEY.

KNIFE.

1,262,390.

Specification of Letters Patent.

Patented Apr. 9, 1918.

Application filed March 13, 1917. Serial No. 154,470.

To all whom it may concern:

Be it known that I, CARL H. ROTH, a citizen of the United States, residing at Newark, in the county of Essex and State of New Jersey, have invented certain new and useful Improvements in Knives; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in knives, and similar tools; and, the present invention has reference, more particularly, to a novel locking or retaining attachment for locking or retaining a knife-blade or other tool in its positively closed or opened relation to the handle by means of such locking or retaining attachment, unless such attachment is first manipulated and retained from its retaining engagement with the knife-blade or other tool.

20

25

The present invention, therefore, has for its principal object to provide in connection with a knife or tool-handle, a simple and efficiently operating locking or retaining means mounted upon a handle for the purpose of locking or retaining a knife-blade or other tool-member in either its closed or opened relation to the said handle, the operation of the locking or retaining attachment being such so that it is easily manipulated to permit the knife-blade or other tool-member to be brought from its locked and closed relation with the handle to its opened and locked relation with the handle, or vice versa.

Other objects of the present invention not at this time more particularly enumerated will be clearly understood from the following detailed description of the present invention.

With the various objects of the present invention in view, the said invention consists, primarily, in the novel locking or retaining attachment for knives and tools, in general, and hereinafter more fully set forth; and, the invention consists, furthermore, in the novel arrangements and combinations of the several devices and parts, as well as in the details of the construction of the same, all of which will be more fully described in the

following specification, and then finally embodied in the clauses of the claim which are appended to and which form an essential part of the said specification.

60 The invention is clearly illustrated in the accompanying drawings, in which:—

Figure 1 is a side elevation of a hunting knife, with the knife-blade in its closed and locked position, said view showing one embodiment of the principles of the present invention; and Fig. 2 is a top-edge view of the same.

Fig. 3 is a longitudinal vertical section through the handle or casing of the knife, 70 with the locking or retaining means in its raised relation, and the pivoted knife-blade represented in its opened relation; and Fig. 4 is a similar view of the parts represented in said Fig. 3, showing the knife-blade open, 75 but locked against movement.

Fig. 5 is a view, partly in elevation and partly in section, of a handle and locking or retaining attachment for detachably securing to said handle to the shank of a suitable 80 tool, as a screw-driver or the like.

Similar characters of reference are employed in the several above described views to indicate corresponding parts.

Referring now to Figs. 1 to 4 inclusive of 85 the said drawings, the reference-characters 1 and 2 indicate the two metal side-members of a knife-handle or casing provided with the end-portions 3, each end-portion 3 having a straight-marginal edge, as 4, and ears, 90 as 5, providing with said straight edges 4 suitably formed offsets 6. Suitably mounted upon the outer faces of the side-faces 1 and 2 are the usual ornamental shells 7, of pearl, celluloid, or any other suitable material, and 95 arranged between the upper edge-portions and the ends of the said side-members 1 and 2, at one end of the handle, is a spring-member 8, the several elements being secured in their assembled relation by means of pins 9, 100 so as to provide the handle with a suitable knife-blade receiving chamber, as 10.

The said spring-member 8, has its portion 11 movably disposed, as in the usual constructions of knives, between the inner surface-portions of the two members 1 and 2, said portion 11 being formed with an upwardly extending part, as 12, and a rearwardly extending finger or extension 13 forming with a part of the upper edge of 110 said portion 11, a receiving space 14. Pivotally mounted upon a pin 15, between the

ears 5, is a locking and releasing trigger or pawl, as 16, formed at one end with a lifting extension 17 adapted to enter the said receiving space 14 and to be moved into lifting engagement with the lower surface-portion of the said finger or projection 13, substantially as indicated in Fig. 3 of the drawings. At its opposite end-portion, the said trigger or pawl is made with a fingerpiece, 10 as 18, usually of the same width as the width of the knife-handle, the said fingerpiece being made with offsets 19 adapted to be moved into frictional contact with the offsets 6 for more positively retaining the said trigger or pawl in its locking relation when the knife-blade 19 is in its closed or opened position.

As shown, the said knife-blade is pivotally mounted upon a pin 20 by means of its shank-portion 21, which is cut away, as at 22, to provide a suitable stop, and to cause this end-portion of the knife-blade, when opened, to readily conform to and fit the lower corner-portion 23 of the movable portion 11 of the spring-member 8, as will be clearly seen from an inspection of Fig. 4 of the drawings.

The operation of the device is very simple and is readily understood from an inspection of the drawings.

Thus, when the trigger or pawl is in its raised position, indicated in Fig. 3 of the drawings, the knife-blade may be readily opened or closed, as will be clearly evident, and when the knife-blade is in its open position, to readily secure the same in its rigid relation to the handle, all that is necessary is to move the trigger or pawl into the position indicated in Fig. 4 of the drawings, 40 whereby the extension 17 is caused to bear down upon the portion 11 of the spring-member 8, so that the part 23 of the said spring-member positively bears upon the edge 24 of the shank-portion 21 of the knife-blade, with the cut away part 22 of said shank-portion snugly fitting against the lower corner-portion 23. To again close the knife-blade, the trigger or pawl is moved into the position indicated in said Fig. 3 of the drawings, whereby the portion 11 of the spring-member 8 is raised sufficiently to permit of the closing of the knife-blade. By again returning the trigger or pawl into its closed relation, as indicated in Figs. 1, 2 55 and 3, the said extension 17 is once more caused to bear upon the upper edge-portion of the part 11 of the spring-member 8, whereby the lower edge-portion of the part 23 is caused to bear firmly upon the edge 25 of the shank-portion 21 of the knife-blade, so that thereby the latter will be rigidly secured within the chamber 10 of the handle of the knife.

In Fig. 5 of the drawings, I have illustrated a device consisting of a suitably

formed handle 41 to which is secured, by means of pins 42, a receiving socket or sleeve-like member 43, said member 43 having a portion extending beyond the part 44 of the handle, and being provided in said part with a projection or lug, as 45. The said socket or sleeve-like member 43 is also provided with a slotted portion 46, across which extends a pivot-pin 47. Pivotally disposed upon said pin is a member 48 75 which is formed at its forward portion with an upwardly projecting part 49, and a rearwardly extending lifting finger or extension 50 forming with the upper surface-portion of said member 48 a receiving space, 80 as 51. The said member 48 is also provided with a pair of pintle-receiving ears 52, and a pintle 53, upon which is pivotally disposed a trigger or pawl of the general construction indicated in Figs. 1 to 4 inclusive. 85 This trigger or pawl, which is indicated by the reference-character 54, is formed at one end with a lifting portion 55 adapted to enter the said receiving space 50 and to be moved into lifting engagement with the lower surface-portion of the said finger or projection 50. At its opposite end-portion the said trigger or pawl is made with a fingerpiece 56, operating in the manner of the construction of the trigger or pawl represented in said Figs. 1 to 4 inclusive, for the proper manipulation of the trigger or pawl and to raise the member or element 48 sufficiently upon its pivot-pin 47, so that a retaining recess or depression 59 in the lower edge-portion of the shank 58 of a screw-driver 57, or other suitable tool, can be lifted out of its engagement with the previously-mentioned portion 45. When the trigger or pawl is in the position indicated in said Fig. 5 of the drawings, the said screw-driver, or other tool, having been previously inserted into position in the socket or sleeve-like member 43, will be suitably retained in its rigid holding or locked engagement with the handle 41, as will be clearly evident from an inspection of said Fig. 5.

From the foregoing description of my present invention it will be clearly seen that I have provided a simply constructed and effectively operating locking or retaining attachment which can be easily manipulated for locking or retaining a knife-blade or other tool in its positively closed or opened relation to a handle; and that, furthermore, my invention is applicable to the attachment of tool-elements or knife-blades to a handle, whether pivotally connected with the handle, in a manner as indicated in Figs. 1 to 4 of the drawings, or whether detachably connected therewith in the manner as represented in Fig. 5 of the drawings.

I am aware that changes may be made in the general arrangements and combinations

of the several devices and parts, as well as in the details of the construction of the said parts, without departing from the scope of my present invention as set forth in the foregoing specification, and as defined in the clauses of the claim, which are appended thereto. Hence, I do not limit my present invention to the exact arrangements and combinations of the several devices and parts as described in the said specification, nor do I confine myself to the exact details of the construction of the said parts, as illustrated in the accompanying drawings.

I claim:—

1. In a knife or tool of the character set forth, a handle-body having a receiving portion in which the shank-portion of the knife-blade or tool-member is disposed, a spring-member forming a part of said handle-body, said spring-member being provided at one end thereof with a rearwardly extending finger and a receiving recess, and a trigger pivotally connected with said handle-body, said trigger having a lifting member adapted to enter said receiving recess and engage the said finger.

2. A knife comprising a handle consisting of a pair of side-members and a spring-member mounted between said side-members to provide a receiving portion, a knife-blade pivoted in said receiving portion, said side-members being provided with upwardly extending end-portions and pinte-receiving ears, said spring-member having a portion extending between the said upwardly extending end-portions of said side-members, said upwardly extending portion of the said spring-member being provided with a rear-

wardly extending finger and a receiving recess, and a trigger pivotally mounted between said pinte-receiving ears, said trigger having a lifting member adapted to enter said recess and engage the said finger.

3. A knife comprising a handle consisting of a pair of side-members and a spring-member mounted between said side-members to provide a receiving portion, a knife-blade pivoted in said receiving portion, said side-members being provided with upwardly extending end-portions and pinte-receiving ears, said spring-member having a portion extending between the said upwardly extending end-portions of said side-members, said upwardly extending portion of the said spring-member being provided with a rearwardly extending finger and a receiving recess, and a trigger pivotally mounted between said pinte-receiving ears, said trigger having a lifting member adapted to enter said recess and engage the said finger.

In testimony, that I claim the invention set forth above I have hereunto set my hand this 10th day of March, 1917.

CARL H. ROTH.
